CLAIM

The ornamental design for a food and beverage menu holder for restaurant tables or the like, as shown and described.

DESCRIPTION

FIG. 1 is a perspective view of a food and beverage menu holder for restaurant tables or the like;

FIG. 2 is a top plan view thereof;

FIG. 3 is a right side elevational view, with the left side being a mirror image thereof;

FIG. 4 is a front elevational view, with the rear being a mirror image thereof;

FIG. 5 is a bottom plan view thereof.
